W. H. FORD

BILLIARD CUE TIP

Filed May 16, 1927

William H. Ford Inventor

By S. E. Thomas

Attorney

UNITED STATES PATENT OFFICE.

WILLIAM H. FORD, OF DETROIT, MICHIGAN.

BILLIARD-CUE TIP.

Application filed May 16, 1927. Serial No. 191,592.

My invention relates to billiard cue tips shown in the accompanying drawings and more particularly described in the following specification and claims.

5 The object of this invention is to provide a billiard cue tip constructed so that it may be readily and securely attached to the cue without glue or other adhesive.

One object of the invention is to construct 10 the cue tip with a screw-threaded stem adapted to engage a ferrule at the end of the cue, the stem being embedded in the cue tip in such manner that it cannot be readily separated therefrom.

15 A further object of the invention lies in the method of constructing the cue tip, whereby a tubular stem is slotted at one end to form prongs which upon being driven into the cue tip are spread apart by a ball 20 lodged in the tip and thereby become securely embedded in the wall of the tip.

With the foregoing and other objects in view which will appear as the description proceeds, the invention further resides in 25 the combination and arrangement of parts and in the details of construction hereinafter described and claimed, it being understood that changes may be made in the precise embodiment of the invention herein disclosed 30 without departing from the spirit of the same.

In the drawings accompanying this specification:

Figure 1 is a longitudinal cross-sectional view 35 through a tubular stem before attaching it to a cue tip, showing one end of the stem chamfered and slotted to form fingers which are spread apart at an angle when driven into the cue tip.

40 Figure 2 is a cross-sectional view through the leather cue tip before being secured to the stem.

Figure 3 is a similar cross-sectional view 45 through the cue tip, with a steel ball lodged in the central cavity of the tip.

Figure 4 is a cross-sectional view through the cue tip showing the fingers formed by slitting the end of the stem, spread apart by the ball to engage the body of the cue tip, 50 upon driving the stem into the latter.

Figure 5 is a fragmentary elevation—partly in section—showing the tip screwed into the ferrule at the end of the cue.

Referring now to the letters of reference placed upon the drawings:

A denotes a cue, B a cue tip preferably formed of leather provided with a central socket B¹ in which is lodged a ball C. D denotes a tubular screw-threaded stem chamfered at one end to form a cutting edge 60 D¹, and also slotted to provide a plurality of fingers D² adapted to be spread apart by the ball when driven into the body of the tip. E is a ferrule fitted to the end of the cue, tapped to receive the stem of the cue tip. 65

Having indicated the several parts by reference letters, the construction and operation of the device will be readily understood.

The stem is secured to the cue tip by driving its slotted chamfered cutting edge into 70 the tip, the ball lodged in the socket of the tip spreading the divided portion of the stem as it enters the tip, that the several prongs of the stem may be securely embedded in the body of the cue tip. The ferrule E fitted 75 upon the end of the cue is tapped to receive the stem of the cue tip which is screwed therein—see Figure 5.

It will be apparent that the tip may thus be firmly secured to the cue and is not apt 80 to be broken away from its stem through use.

Having thus described my invention what I claim is:

1. A device of the character described, 85 comprising a cue tip of yieldable material having a central socket; a ball lodged in the socket; and a screw-threaded stem slotted at one end to form fingers adapted to be spread outwardly at an angle into the body of the 90 cue tip upon driving it against the ball lodged in said socket.

2. A device of the character described, 95 comprising a cue tip of yieldable material having a central socket; a ball lodged in the socket; and a screw-threaded stem slotted at one end and chamfered to form fingers with a cutting edge, adapted to be spread outwardly at an angle into the body of the cue tip upon driving it against the ball lodged 100 in said socket.

In testimony whereof, I sign this specification.

WILLIAM H. FORD.
